UNITED STATES PATENT OFFICE.

TETSUSABURO WATANABE, OF NEW YORK, N. Y.

FOUNTAIN-PEN.

1,038,034.

Specification of Letters Patent. Patented Sept. 10, 1912.

Application filed September 23, 1911. Serial No. 650,947.

To all whom it may concern:

Be it known that I, TETSUSABURO WATANABE, a subject of the Emperor of Japan, residing at New York, in the county of New York and State of New York, have invented a certain new and useful Improvement in Fountain-Pens, of which the following is a specification.

The invention relates to fountain pens, and consists in the combination with a suitable holder, or stock, of a cup-shaped ink-holding reservoir supported on one end of the holder, an ordinary pen held in the holder so that it forms a cover for the open side of the reservoir, and a sliding sleeve on the holder constructed to retain the pen in reservoir-covering position and to be retractable to permit said pen to fall away by gravity from the reservoir, and so release itself without requiring to be grasped by the operator.

The invention further consists in the construction whereby the reservoir is made adjustable with reference to the pen point, and the arrangement of the retracting spring for the sleeve within a metal thimble carried by the holder, as more particularly pointed out in the claim.

In the accompanying drawings—Figure 1 shows the manner of manipulating the device to release the pen. Fig. 2 is a perspective view of my device. Fig. 3 is a perspective view of the outer sliding sleeve. Fig. 4 is a perspective view of the spring holding thimble. Fig. 5 is a perspective view of the end of the pen-holder handle, to which the parts shown in Figs. 3 and 4 are applied. Fig. 6 shows the parts shown in Figs. 3, 4 and 5 assembled and in longitudinal section, with the pen and ink holding cup and supporting rod in elevation.

Similar numbers of reference indicate like parts.

Near the end of the pen-holder handle 1 is formed a circumferential groove 2. To said handle is applied the metal thimble 3, which is secured by turning the edge thereof inwardly to form a flange 4 which enters said groove. To facilitate this turning in, the thimble may be split at several points around said edge, as shown in Fig. 4. The outer end of the thimble is closed and provided with a polygonal opening 5. In the wall of the thimble and extending from the

closed end are made elongated slots 6, and between the same is a recess 7. The inclosing sleeve 8 at its outer end is provided with in-turned lugs 9 which enter the slots 6. The ink fountain 10 is cup-shaped and is provided at its outer end with a lip 11. To said fountain cup is secured a rod 12 of polygonal cross section, which is threaded at 13 over a part of its length to receive a nut 14. The end portion of said rod fits and may be frictionally held in an opening 15 in the handle 1. A helical spring 16 is placed within the thimble 3.

In assembling the parts, the rod 12 is passed through the opening 5, and the nut 14 is adjusted on the threaded portion 13 thereof so that when said rod is inserted in the opening 15 in the handle, the fountain cup 10 will stand, as shown in Fig. 2, in proper relation to the pen 17. The spring 16 being put into the thimble, said thimble is secured in place on the handle by the flange 4, as already described. The sleeve 8 is then placed over the thimble, with its lugs 9 entering the slots 6 and with the tongues 18 formed in its wall engaging a rib 19 on the holder handle. Finally, the pen 17 is inserted in the recess 7, and hence between the thimble and the sleeve 8. The lip 11 of the fountain cup then meets or very nearly meets the pen at a point near the nib thereof, and covers the usual opening 20 formed in the pen at the end of the slit therein while the pen forms a cover for the ink-holding cup.

In operating the device, the pen is dipped in the ink in the ordinary way to fill the cup. Pressure on the nib in writing springs said nib outwardly from the lip 11, thus permitting the ink to flow from the cup downwardly to the pen point. In order to remove the pen without soiling the fingers of the operator, the handle 1 is grasped in one hand, and the sleeve 8 is slid along said handle, as shown in Fig. 1, until the pen releases itself from the recess 7 and falls from the pen-holder. The lugs 9 then travel in the slots 6 and engage the helical spring 16, which thus becomes compressed. After the pen is released, the spring 16 restores the sleeve 8 to its former position. The tongues 18 retain the sleeve 8 on the holder. When the pen is removed, access to the interior of the fountain cup may be had for cleansing the same.

I claim:

A holder, a thimble inclosing the end of
said holder and secured thereon, an ink
holding cup shape reservoir, a rod carry-
ing said reservoir, and extending through
the end of said thimble into said holder,
said rod having a portion screw threaded,
a nut upon said screw-threaded portion

adapted to be used in adjusting said reser-
voir.

10

In testimony whereof I have affixed my
signature in presence of two witnesses.

TETSUSABURO WATANABE.
